United States Patent Office.

WEBB BROOMHALL, OF CIRCLEVILLE, OHIO, ASSIGNOR TO HIMSELF AND ACKER KING, OF SAME PLACE.

Letters Patent No. 90,491, dated May 25, 1869.

IMPROVED COFFIN.

The Schedule referred to in these Letters Patent and making part of the same.

To all whom it may concern:

Be it known that I, WEBB BROOMHALL, of Circleville, in the State of Ohio, have invented a new and useful Improvement in Coffins; and I do hereby declare that the following is a full, clear, and exact description of the same, reference being had to the accompanying drawings, and letters of reference marked thereon, making a part of this specification, in which—

Figure 1 is a transverse vertical section of a coffin, with my improvement applied;

Figure 2 is a detached view of one of my flanged and slotted pieces; and

Figure 3, an elevation of one end of the coffin, showing the lock.

This invention consists in a combination of flanged metallic pieces and flanged metallic slotted pieces, so arranged upon the under side of the cover and the inside of the coffin, as that the flanges of the former may pass under the flanges of the latter on moving the cover to its place, and thus hold it securely without the use of screws.

To enable those skilled in the art to make and use my invention, I now proceed to describe its construction and operation.

Similar letters, in the drawings, refer to like parts.

In the drawings—

a a are two oblong pieces of metal, screwed to the under side of the cover, longitudinally of the same, of a length of one and a half inch, one-quarter of an inch wide, and one-quarter of an inch thick, which pieces are furnished with flanges *a'*, one to each lower and outer corner.

To the inner surface of each of the sides of the coffin is screwed a slotted flat piece of metal, *b*, say one and a half inch long and three-quarters of an inch wide, with a flange, *b'*, at its upper end, flush with the top of the coffin.

If the cover be placed on the coffin so that the flanges *a'* clear the flanges *b'*, and then be shoved endwise, so as to bring the former under the latter, it is

plain that the two sets of flanges will hold the cover down.

At the opposite end, a staple may be attached to the under side of the cover, at the centre thereof, and one of the slotted and flanged pieces may be secured to the end of the coffin, also at its centre, so that the flange may enter the staple when the cover is moved into position, which connection serves to secure the cover from lateral displacement.

As a matter of precaution, to prevent the corpse from pressing out the sides of the coffin, it may sometimes be found expedient to adjust the slotted and flanged pieces in recesses, sunk transversely of the cover, and so that the flanges may come just outside of and in contact with the sides of the coffin.

The reason for making the pieces *b* slotted is that they may be brought into exactly the proper position by the action of the flanges *a'*, passing under the flanges *b*, the screws in the pieces *b* being driven at first only far enough to just hold them from slipping, but not to prevent the flanges *a'* from drawing them into place. This done, the pieces *b* may be tightly screwed on.

At one end of the cover is an eye, *d'*, projecting downward, and on the end of the coffin, underneath, is a hook, *d*, which may be turned up in order to pass this, (the eye,) and then turned down to hold it. When this is done the attachment of the cover to the coffin is complete, being effected in a very expeditious manner and without the aid of screws. The cover may be taken off in an equally-easy way.

What I claim as new, and desire to secure by Letters Patent, is—

1. The combination of the flanged pieces *a a'* with the flanged and slotted pieces *b b'*, as and for the purpose set forth.

2. The combination of the foregoing with the hook and eye *d d'*, substantially as described.

Witnesses:
